UNITED STATES PATENT OFFICE.

MAURICE MAYOROWITZ, OF NEW YORK, N. Y.

DETACHABLE HEEL FOR SHOES.

Application filed February 17, 1925. Serial No. 9,800.

The invention relates to boots and shoes. An object of the invention is to provide a new and improved detachable heel arranged to permit a dealer in boots and shoes to readily provide a boot or shoe with a leather heel or with a rubber heel or a heel of other material according to the desires of the customer.

Another object is to enable the user of a boot or shoe to readily replace a worn-out heel by a new one.

A further object is to securely hold the detachable heel in place and to prevent moisture, dust or other extraneous matter from passing into the joint formed between the detachable heel and its support.

In order to accomplish the desired result, use is made of a plate attached to a lift secured to the sole of the boot or shoe, the plate being provided with longitudinally extending bayonet slots, a detachable heel provided with headed studs engaging the said bayonet slots, and removable fastening means extending through the sole, the sole lift and plate and engaging the said detachable heel. Use is also made of springs struck up on the plate and surrounding the terminals of the said bayonet slots to be engaged by the heads of the said studs to draw the detachable heel firmly against the sole lift.

A practical embodiment of the invention is represented in the accompanying drawings forming a part of this specification, in which similar characters of reference indicate corresponding parts in all the views.

Figure 1 is a perspective view of the heels attached to the shoes;

Fig. 2 is a vertical longitudinal section through the heel;

Fig. 3 is a horizontal section on the line 3—3 of Fig. 2;

Fig. 4 is a similar section on the line 4—4 of Fig. 2;

Fig. 5 is a vertical transverse section on the line 5—5 of Fig. 2;

Fig. 6 is an inverted plan view of a modified form of construction;

Fig. 7 is a sectional view of a modified form of stud;

Fig. 8 is a sectional view taken on the line 8—8 of Fig. 6;

Fig. 9 is a sectional view taken on the line 9—9 of Fig. 6; and

Fig. 10 is a partial section of a still further modified form.

The forms of the invention shown in the

drawings are preferred forms, although it is understood that other modifications in the construction and arrangement of the parts and in the character of the materials used may be adopted wthout departing from the spirit of the invention as set forth in the appended claims.

To the underside of the heel end of the sole 10 of a boot or shoe 11 is secured in the usual manner a sole lift 12. The sole lift is provided with an opening 13. A metallic plate 14 fits on to the lower face of the sole lift and is preferably made of sheet metal or like resilient material, and this plate is secured to the lift in any desired manner, such as by nails 15.

The plate 14 is provided with transversely extending bayonet slots 16 (see Figs. 3 and 6). These slots register with the opening 13 formed in the heel lift 12. The plate 14 is provided with spherical spring seats 17 which are struck up out of the metal of the plate itself, preferably around the small rear portions of the bayonet slots 16, these struck-up portions being bent from the plate 14 in the direction of the opening 13 in the heel lift.

The bayonet slots are adapted to be engaged by studs 18 having heads 19 projecting upwardly from the face of a detachable heel 20. These studs, as shown in Fig. 2, are formed wth an anchor plate 21 and a stem 22, which may be slotted to further insure the seating of the stud in the heel. This heel may be made of rubber or of other material.

When it is desired to place the detachable heel 20 in position against the plate 14, the heads 19 of the studs 18 are engaged with the large ends of the bayonet slots, and then the detachable heel is pushed laterally to cause the studs to enter the smaller portions of the slot and to cause the heads 19 to travel upon the spring seats 17 whereby the heel is drawn upward against the plates so as to firmly engage it to form an exceedingly tight joint.

In practice the boot or shoe is provided by the manufacturer with the plate 14 in place and detachable heels with studs 18 thereon are furnished to the dealer so that the latter can readily attach a leather heel to the boot or shoe, according to the desire of the customer. It will also be noticed that the user of the shoe can readily remove said heel as it becomes worn and replace it by a

new one, it only being necessary to release the latch means to be hereinafter described, and then to lift the heel off the shoe by sliding it laterally until the heads of the studs 5 register with the front ends of the bayonet slots. Another heel can thereafter be placed into engagement with the shoe.

As shown in Fig. 3 particularly, it will be noticed that a latching or locking spring 10 finger 23 is struck from the metal of the plate 14 and that its forward free end is adapted to normally lie over the front end of one of the bayonet slots to close the same. A hole 24 is provided in the sole lift 15 12 and leads to a point adjacent the side of this locking finger, a portion of which adjacent the heel is bent up as at 25 (see Fig. 2) to form a sort of cam surface which can be engaged by a pin or rod which projects 20 through the hole 24 to move the end of the latch finger. This latch finger, as shown in Fig. 5, is adapted to lie closely adjacent the stud 18 when it is in place.

In the operation of attaching the heel, 25 as the head 19 of the stud 18 is inserted into the forward end of the bayonet slot in association with which the latch finger 23 is disposed, this finger is temporarily moved aside to the position shown in dotted lines 30 in Fig. 5, after which the stud is moved to the small end of the slot. The spring latch then springs back into place and lies with its free end adjacent the stud to hold it and the other studs in the proper positions 35 in their respective slots.

In the form of the invention shown in Figs. 6 and 8, I provide the spring finger 26 independent of the bayonet slots and adjacent a separate aperture 27 into which a 40 special stud 28 is insertable, the stud being shown in Fig. 8, and provided with an upwardly and divergently tapered head.

As shown in Fig. 10, the end 29 of the spring finger 30 is bent up to lie snugly against the head 31 of the stem 32. As 45 shown in Fig. 9, it will be observed that the spring seat 33 is countersunk to form a recess or seat for the head 19. This formation of a special recess or seat for the head will further secure the proper fixation of the 50 heel to the sole lift.

In Fig. 7 I show a stud 34 which has a finger plate 35 adapted to be embedded in the heel, especially when this heel is made of rubber and can be molded around the 55 stud.

What I claim is:-

1. In combination, a heel having headed studs, a sole plate having bayonet slots, said studs adapted to be engaged in said slots, 60 and a spring finger struck from the metal of the plate itself adapted to engage with one of said studs after it has been engaged in its respective slot, and an anchor plate on the stud engaging the sole plate for aiding 65 in retaining the sole plate rigidly on the heel.

2. In combination, a heel lift having headed studs provided with anchor plates flush with the inner surface of a heel lift, 70 a sole plate having bayonet slots to receive the headed studs, said sole plate being provided with seats for the heads of the studs, said seats projecting from the inner face of the sole plate, the arrangement and construction of the seats and the heads relative to the anchor plates being such when the heads are forced into the seats the anchor plates will be drawn up with considerable force against the sole plates thus preventing 75 80 loosening of the heel lift from the anchor plates.

MAURICE MAYOROWITZ.
